CLAIM

The ornamental design for a drink container with handle and lid, as shown and described.

DESCRIPTION

FIG. 1 is a top perspective view of my new design for a drink container with handle and lid;

FIG. 2 is a front side elevation view thereof;

FIG. 3 is a rear side elevation view thereof;

FIG. 4 is a left side elevation view thereof;

FIG. 5 is a right side elevation view thereof;

FIG. 6 is a top plan view thereof;

FIG. 7 is a bottom plan view thereof; and,

FIG. 8 is a bottom perspective view thereof.

The portions of the drink container with handle and lid shown in broken line form no part of the claimed design.

1 Claim, 6 Drawing Sheets
